PANTY

Seymour Katz, Chicago, Ill., assignor to Phil-Maid, Inc., Chicago, Ill., a corporation of Delaware

Application June 5, 1953, Serial No. 25,348

Term of patent 3½ years

(Cl. D3—17)

To all whom it may concern:

Be it known that I, Seymour Katz, a citizen of the United States, residing at Chicago, in the county of Cook and State of Illinois, have invented a new, original, and ornamental Design for a Panty, of which the following is a specification, reference being had to the accompanying drawing forming a part thereof.

The figure on the drawing is a front elevational view of a panty, showing my new design.

The back of the panty is plain and unornamented.

I claim:

The ornamental design for a panty, substantially as shown and described.
